SURFACE ORNAMENTATION OF WALLS, &c.

No. 16,415.

Patented Dec. 15, 1885.

UNITED STATES PATENT OFFICE.

FREDERICK MANKEY, OF WILLIAMSPORT, PENNSYLVANIA.

DESIGN FOR SURFACE ORNAMENTATION OF WALLS, &c.

SPECIFICATION forming part of Design No. 16,415, dated December 15, 1885.

Application filed November 2, 1885. Serial No. 181,718. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photograph.

A and B are triangular pyramidal elevations of the form of isosceles triangles, and placed base to base, with an intermediate channel, C.

D E F G are triangular pyramidal elevations, between which are channels H I. The elevations D E F G, conjointly, have the appearance of a Maltese cross, and are separated from the adjacent pairs of elevations, A B, by channels J. The pairs of elevations A B and sets of elevations D E F G are disposed alternating in a row. There may be several such rows, as K L, with intervening channels, M,

as shown. The elevations A B in one row are opposite the elevations D E F G in the adjacent row.

I claim—

1. The design for surface ornamentation of walls, &c., substantially as herein shown and described, which consists in the elevations A B, with intervening channel, C, the elevations D E F G, with intervening channels, H I, and the channels J.

2. The design for surface ornamentation of walls, &c., substantially as herein shown and described, which consists in the elevations A B, with intervening channel, C, the elevations D E F G, with intervening channels, H I, and the channels J, the said elevations being in rows, as K L, with intermediate channels, M.

FREDERICK MANKEY.
